UNITED STATES PATENT OFFICE.

JENS PETER HANSEN, OF COPENHAGEN, DENMARK.

APPARATUS FOR DEVELOPING, FIXING, AND WASHING OF PHOTOGRAPHIC FILMS AND PLATES.

1,305,095.

Specification of Letters Patent. Patented May 27, 1919.

Application filed September 4, 1918. Serial No. 252,654.

To all whom it may concern:

Be it known that I, JENS PETER HANSEN, a subject of the King of Denmark, and residing at Nr. 10 Jacoby's Alle, Copenhagen, Denmark, have invented certain new and useful Improvements in Apparatus for Developing, Fixing, and Washing of Photographic Films and Plates, of which the following is a specification.

10 My invention concerns an apparatus to be used for the developing, fixing and washing of photographic films and plates.

In distinction from the apparatus for this use, now known my invention has the advantage, that films or plates in single envelop may be inserted and developed in full daylight and also that considerably smaller quantities of solutions for developing and fixing are needed, owing to the form of the 20 tank.

The apparatus is shown in the drawing in one form of execution, but it will be understood, that the form and fitting-up of the separate parts need not to be exactly as shown in the drawing; but all the separate 25 parts may be altered and varied in different ways, without the principle for the invention being deviated from.

The invention is shown in the drawing, 30 where:

Figure 1 shows a side view of the apparatus.

Fig. 2 the same in vertical cross section on the line 2—2 in Fig. 1.

35 Fig. 3 the same seen in top view, with the cover removed.

Fig. 4 the same with the cover in place.

Fig. 5 shows a vertical cross section through the upper part of the tank of the 40 apparatus with the cover and the lid removed and a clip mounted on the tank for fastening of the fixed films during the washing.

Fig. 6 shows the clip shown in Fig. 5, seen 45 from below,

Fig. 7 is a cross section in enlarged scale, of one of the india rubber cushions.

Fig. 8 is a front view of a film envelop,

50 Fig. 9 is a longitudinal section of the same, and

Fig. 10 is a sectional view of the apparatus with the tank broken away and showing several of the film envelops held therein.

On the drawing 1 is a tank which preferably may be wedge-shaped—if not double

wedge shaped—and with a hole in the side close to the bottom, from which a small tube 2 is connected with a funnel 3, fastened to the side of the vessel. The bottom may slope downward against said hole in order to 60 drain the tank thoroughly.

The tank is provided with a cover 4, which consists of a frame with cylindrical india rubber cushions 5 firmly secured in bearings in the frame, which cushions preferably may 65 be made of very soft rubber on hard cores 6, of wood for example and which may be easily applied fixed or movable in the frame of the cover.

The core 6 is rectangular, while the rubber layer is of oval cross-section, so that two air cushions 11 (Fig. 7) are formed, which tend to secure a yielding and light-tight connection.

Above the cover is a sliding lid 7 in the 75 interior of which is a notch with incisions 8 so that there are a pair of incisions above the middle of each rubber cushion, whereby a better light-tightness between the cushions is attained.

80 With my invention, film envelops shown in Figs. 8 and 9 are designed to be used. These envelops α consists of a back plate 1' of opaque thick paper having a holding ribbon 6', and a cover-plate 9'. The longitudinal edges of this back plate are bent and one short edge 4' is also bent, and the longitudinal edges and the edge 4' are then fastened together, and along the opposite short edge of the back plate the longitudinal 90 edges are connected by a ribbon 6'. An envelop is thereby formed to receive the film, 7', which is held therein by the bendings of the longitudinal edges, the edge 4', the ribbon and a bending 8' of the short edge of the 95 back plate. Between the film 7' and the several bendings and ribbon 6' a cover-plate 9' is inserted. This cover-plate consists of thick paper, one short edge of which has a bending as shown at 10'. The bending 10', 100 when the cover-plate is drawn out, cooperates with the bending 8' on the back plate and prevent this cover plate from being drawn entirely out, and light-tightness during exposure is thereby secured.

105 The opposite short edge of the cover-plate has a tongue 11', which is bent down over the back side of the back plate in order to obtain light-tightness, and besides it serves as a finger hold during the displacement of 110

the cover plate. To place a film envelop in the apparatus, the cover 4 is removed and turned over, and the tongue 11' of the cover plate 9' having been bent outward, the film envelop is inserted between two cushions 5 with the tongue 11' of the envelop engaging the notches 8 of the lid 7, which are above the next adjacent cushion 5, as shown in Fig. 10.

10 When the developing has been finished, the tube 2 is removed from the funnel 3, and is bent downward so that the liquid runs out. Then the tube is again applied on the funnel, in order that the fixing-bath 15 may be filled in through this.

When the exposed and developed films or plates have been fixed, they must be washed, and this is done in the same tank, the cover 4 and the lid 7 being removed, and the films, 20 which being taken out from the envelops, are hung up in a clip 9, which is provided with cheeks 10, which clip is placed on the upper edge of the tank as shown on Figs. 5 and 6, after which water is led through the apparatus.

Owing to the wedge-form of the apparatus its capacity is much smaller than that of usual, corresponding tanks, so that less quantities of chemicals are employed and by 25 using the film envelops of a special kind perfect light-tightness during the developing may be secured.

Having now described my invention I desire to secure by Letters Patent.

30 1. An apparatus for developing, fixing and washing a film or plate in an envelop having a flexible cover plate, said apparatus comprising a tank, a frame on the tank, cushions carried by the frame and between 35 which the enveloped film or plate is introduced, a member above the frame and hav-

ing means for engaging a portion of the said cover plate to bend the same over the cushion.

2. An apparatus for developing, fixing 45 and washing a film or plate in an envelop having a flexible cover plate, said apparatus comprising a tank, a frame on the tank, cushions carried by the frame and between which the enveloped film or plate is introduced, and a removable lid above the frame and having a cut out and notched portion, the notches of which are offset from the meeting edges of adjacent cushions, whereby a portion of said cover plate will be bent 55 over an adjacent cushion to exclude light.

3. In an apparatus for developing, fixing and washing a film or plate in an envelop, a tank, a frame on the tank, and cushions carried by the frame, said cushions each 60 comprising a rigid core and a yielding covering.

4. In an apparatus for developing, fixing and washing a film or plate in an envelop, a tank, a frame carried by the tank, and 65 cushions carried by the frame, each cushion comprising of a rigid core and a yielding covering for the core, the core and covering being of different cross sections, whereby to form air spaces between them.

5. In an apparatus for developing, fixing and washing a film or plate in an envelop, a tank, a frame on the tank, and cushions carried by the frame, each cushion consisting of a rectangular rigid core, and an oval 70 covering of rubber.

In testimony whereof I affix my signature in presence of two witnesses.

JENS PETER HANSEN.
